UNITED STATES PATENT OFFICE

111,805

DESIGN FOR A HAIR DRYING APPARATUS

Milton H. Cearn, Chicago, Ill.

Application August 9, 1938, Serial No. 79,198

Term of patent 7 years

To all whom it may concern:

Be it known that I, Milton H. Cearn, a citizen of the United States and a resident of Chicago, in the county of Cook and State of Illinois, have invented a new, original, and ornamental Design for a Hair Drying Apparatus, of which the following is a specification, reference being had to the accompanying drawing, forming a part thereof, and in which:

Fig. 1 is a perspective view of a hair drying apparatus showing my new design;

Fig. 2 is a fragmentary side elevation as viewed from line 2—2 in Fig. 1; and

Fig. 3 is a fragmentary end elevation viewed from line 3—3 of Fig. 2.

I claim.

The ornamental design for a hair drying apparatus, as shown and described.

MILTON H. CEARN.
